UNITED STATES PATENT OFFICE.

WILLIAM HENRY ALBEE, OF MARLBORO, MASSACHUSETTS, ASSIGNOR TO KOEHLER MANUFACTURING COMPANY, OF MARLBORO, MASSACHUSETTS, A CORPORATION OF MASSACHUSETTS.

PROCESS OF APPLYING FOOTBALL CLEATS TO SHOES.

Application filed October 4, 1922. Serial No. 592,333.

This invention relates to football cleats and to processes of securing them to a shoe.

The usual process heretofore practiced of equipping a shoe with a football cleat has 5 consisted in cementing together pieces of leather to build up a block or blank of the desired height, then nailing this assembled piece to the bottom of a shoe, and finally trimming said block either with a knife or 10 with a hammer and chisel to form a cleat of the desired shape and size. This process obviously requires a great deal of labor, it produces cleats which are not uniform in size or shape, and there is great danger of 15 cutting the sole or heel of a shoe in trimming the cleat. In fact, this process really involves performing the greater part of the manufacturing operations on the cleat after it has been secured to the shoe.

20 The present invention aims to improve this process with a view to reducing the expense involved, improving the quality of the work produced, and eliminating the danger of injuring the shoe.

25 The nature of the invention will be readily understood from the following description when read in connection with the accompanying drawings, and the novel features will be particularly pointed out in the appended claim.

30 Referring now to the drawings,

Figure 1 is a perspective view of a cleat blank or block;

Fig. 2 is a perspective view of the block 35 after it has been trimmed;

Fig. 3 is a perspective view of a completed cleat;

Fig. 4 is a transverse, vertical, cross sectional view of the cleat shown in Fig. 3;

40 Fig. 5 is a cross sectional view showing the manner in which the cleat preferably is secured to the sole of a shoe; and

Fig. 6 is a cross sectional view through 45 the cleat and a portion of the sole after the attaching operation has been completed.

According to the present process the manufacturing operations on the cleat are first completed and subsequently it is secured to the bottom of a shoe.

50 The cleat may be made of any suitable material but usually consists of several lifts of leather 2 cemented together, one on top of the other, to form a blank of the desired dimensions. This blank is then run through

or between cutters which trim its edges, giving it the shape of a frustum of a cone, as shown in Fig. 2. The cleat is next molded or compressed in suitable dies or molds for the purpose of consolidating the stock, and of concaving the bottom of the cleat, as indicated at 3 in Figs. 3 and 4. That is, the bottom is inwardly curved, being given substantially the shape of the surface of a section of a cylinder, the axis of which extends lengthwise of the cleat, so that the two edges 55 at opposite sides of the base of the cleat lie below the remainder of the base. This makes the base of the cleat conform substantially to the curvature of the sole of a shoe so that when it is nailed on the sole the edges 60 of the cleat will hug the sole tightly. The concave shape of the base also has the advantage of preventing the edges of the cleat 65 from curling up when the cleat is nailed to the shoe, which has been an objectionable 70 feature of prior constructions.

During the molding operation and while the surfaces of the cleat are confined against distortion, several holes, usually four, are punched almost through the cleat from the 75 upper surface thereof, these holes being designed to receive the nails or other fastenings by means of which the cleat ultimately 80 will be secured on the bottom of the shoe. The cleat in this condition forms an article 85 of commerce. I prefer, however, before marketing the cleat, to drive into it the fastenings by means of which it is to be secured to the shoe, thus producing a cleat 90 that is entirely self-contained. A particular advantage of this arrangement is that the 95 nails can all be driven at once by machinery so that a substantial saving in labor is effected, the nails are driven uniformly, and the attaching of the cleat to the shoe is facilitated. The punching of the holes practically through the cleat avoids the danger 100 which otherwise would be present of the nails being diverted during the driving process, with the consequent damage to the cleat and probably also to the shoe. Figs. 3 and 4 show the cleat with nails 4 partially driven therethrough, the head and a substantial length of each nail projecting above 105 the upper surface of the cleat. These nails preferably are driven into the position shown in Figs. 3 and 4 while the base of the cleat rests on a curved support so that the curva-

ture of the bottom of the cleat will not be distorted. The points of the nails may prick through the bottom face of the cleat.

The entire trimming operation need not precede the molding; in fact it is preferable under some circumstances to trim the block longitudinally, then compress it, and subsequently, while the blank is in the more consolidated and stable condition, to trim the ends. The holes are punched later.

For the purpose of affixing a cleat to the bottom of a shoe an iron last 6, Fig. 5, is inserted within the shoe, indicated diagrammatically at S in said figure. The cleat C is placed in the desired position on the shoe bottom, and the nails 4 are then driven through the cleat and into the shoe sole, the points of the nail clenching on the surface of the iron last 6. There is considerable danger of splitting the cleat during this operation, or at least distorting it so much that it presents an unsightly appearance, and in order to overcome this objection I prefer to confine the lateral faces or edges of the cleat while the fastenings are being driven.

For this purpose the tool shown in Fig. 5 may conveniently be used, although this step of the process may be performed in any other suitable manner. It will be observed that the tool comprises a body 7 having a cavity 8 in its lower end in which the cleat C fits snugly. This body is provided with a series of holes 10, into the lower ends of which the nails 4 project, a series of drivers 12 being slidably mounted in these holes. These drivers are secured to a driver bar 14 which slides within the body 7, and the bar is provided with a head 15 which may conveniently be struck by a mallet, thus driving all four nails at once. Since the cleat fits snugly in the recess 8, the walls of this recess confine the lateral faces of the cleat against distortion while the fastenings are being driven. The stroke of the driver bar 14 is limited by the engagement of the head 15 with the upper

end of the body 7, so that the distance to which the nails can be driven by the drivers is gaged from the lateral inclined faces of the cleat. Injury to the cleat due to over-driving of the nails, therefore, is avoided.

Fig. 6 shows the cleat in cross section after it has been secured to the bottom of the sole of a shoe S, the end 5 of the nail 4 being clenched, as clearly illustrated. By shaping the cleat, as above described, and supporting its faces against distortion during the operations of punching holes therein and driving fastenings therethrough, any danger of splitting the cleat, or distorting it substantially, is completely avoided. Consequently, when the process has been completed, the cleat presents a neat and finished appearance. Furthermore, this invention not only results in giving the cleats a uniform and more satisfactory appearance, but it applies them to the shoe in such a manner that they are stronger and there is substantially less danger of their becoming loosened than when applied by the processes heretofore practiced. Any danger of cutting the shoe is completely avoided, and damage to the shoe or the cleats due to improper driving of the fastenings is eliminated. Furthermore, the cleats provided by this invention are preferred by the trade because they can be applied to the shoe more easily, particularly when they are loaded with nails, as above described.

Having thus described my invention, what I desire to claim as new is:

That improvement in the process of securing a tapered football cleat to a shoe which consists in placing the cleat in the desired position on the bottom of the shoe, driving fastenings through the cleat and into the bottom of the shoe, supporting the tapered faces of the cleat against distortion while said fastenings are being driven, and gaging the stroke of the driving means from said tapered faces of the cleat.

WILLIAM HENRY ALBEE.
